UNITED STATES PATENT OFFICE.

WALTER S. ADAMS, OF PHILADELPHIA, PENNSYLVANIA, ASSIGNOR TO THE J. G. BRILL COMPANY, OF PHILADELPHIA, PENNSYLVANIA.

CAR-TRUCK.

No. 926,838.

Specification of Letters Patent.

Patented July 6, 1909.

Application filed September 18, 1908. Serial No. 453,679.

To all whom it may concern:

Be it known that I, WALTER S. ADAMS, a citizen of the United States, and a resident of the city and county of Philadelphia and State of Pennsylvania, have invented a new and useful Improvement in Car-Trucks, of which the following is a specification.

The object of my invention is to simplify and improve a truck of the kind known as 10 the "Master Car Builder's type," which object is accomplished by my invention, one embodiment of which is described below.

For a more particular description of my invention, reference is to be had to the accompanying drawings, forming a part hereof, in which:

Figure 1 is a plan view of a truck embodying my improvements. Fig. 2 is a side elevation of the same. Fig. 3 is a plan view, 20 partially in section, of a journal box of my improved truck. Figs. 4, 5 and 6 are details of construction. Fig. 7 is a side view of the axle box shown in Fig. 3. Fig. 8 is a front end elevation of the same. Fig. 9 is a sectional view taken on the line 9—9 of Fig. 1, looking in the direction of the arrows, some parts being omitted to simplify the illustration. Fig. 10 is a sectional view taken on the line 10—10 of Fig. 9, looking in the direction 30 of the arrows. Figs. 11, 12 and 13 are end and side elevations and a plan view respectively, of the equalizing spring cap and semi-elliptic spring holder. Figs. 14 and 15 are a side elevation and plan view respectively, of 35 the equalizing spring seat.

Throughout the various views of the drawings, similar reference characters designate similar parts.

My improved truck 1 is provided with the 40 usual car wheels 2 united by axles 3 which run in axle boxes 4 in the conventional manner. These axle boxes support the frame of the truck 5 as well as the equalizing bars 6. The equalizing bars 6 carry the equalizing 45 springs 7 which carry by a special form of caps 8, the upwardly arched semi-elliptic springs 9 from which the bolster 10 is supported by means which will be described below. By this construction, the load upon 50 the bolster is taken directly to the spring system of the car and from that to the equalizing bars without placing any stresses of any kind whatever on the frame of the truck.

The details by which this is carried out will now be pointed out.

The axle boxes 4 are each provided with a downwardly extending lug 11 which is perforated and adapted to be secured to a bracket 12 by a bolt 13 and the bracket 12 is riveted to a tie-bar 14 which unites the ears 11 of the 60 two axle boxes on the same side of the truck. The bolt 13 is preferably provided with a suitable lock-nut 15, and washer 16, a coil spring 17 and a second washer 18 so that the bracket 12 is firmly held against the lug 11. 65

The upper surfaces of the axle box 4 are each provided with a cylindrical surface as shown in dotted lines in Figs. 2 and 8 and on these cylindrical surfaces are saddles 19 which are brackets to which equalizing bars 6 are 70 riveted by rivets 20.

The frame 5 of the truck 1 passes between the equalizing bars 6 and it is, in part, downwardly disposed close to the axle boxes 4 but does not touch the same except to rub 75 against the sides thereof and the lower ends of the frame 5 are turned horizontally and bolted to extensions 21 of the tie bars 14 by bolts 22. This is sufficiently strong because as stated above, the frame 5 carries no load, 80 but is made so as to resist horizontal stresses. The frame 5 may terminate here or may be extended around so as to join with the other side of the truck whereby additional strength and stiffness are acquired and also additional weight. 85

It is obvious that if desired, the tie bars 14 may be duplicated, one being placed on each side of the lugs 11. This also gives additional strength, as well as additional weight. 90

The equalizing bars 6 do not terminate with the axle boxes 4, but extend downwardly beyond the same and then horizontally to form extensions 23 on which rest the motor supports 24. 95

The frame 5 of the truck consists of top chords 25 united by crossings or transoms 26 and these crossings or transoms 26 rest flat on the top chords 25 and run on these to points near the axle boxes. The transoms 100 26 and top chords 25 are preferably riveted together by rivets 27 so that under no circumstances can these parts become separated or work loose. Neither the transoms nor the top chords require any vertical webs 105 because these parts are subjected to hori-

zontal stresses only. The transoms 26 are provided with suitable wear plates 28, which are provided with a number of holes set at varying distances from that surface of the wear plate which engages the bolster 10. The holes are disposed on the segment of a circle, so that by moving the wear plates to and from the bolster and securing the wear plate by the bolts provided for, the adjustment of the wear plates to and from the sides of the bolster may be accomplished.

The bolster 10 is supported in the following manner. The equalizing bars 6 near the axle boxes 4, shown in Fig. 2, are provided with equalizing spring seats 29 made of the ordinary construction or they may be provided with perforated lugs 30 and 31 to enable these seats to be secured to the equalizing bars as firmly as desired. These seats are also provided with central perforations 32 through which a tie bolt 33 extends as shown in Fig. 10. The spring seats 29 each carry a coil spring 7 which corresponds to the ordinary equalizing spring of a Master Car Builder's truck. The springs 7 are covered with spring caps 8 each of which is as follows: Each is provided with a central perforation 34 through which the tie-bolt 33 passes and they are provided with perforated ears 34 adapted to surround pins, not shown, on the lower surfaces of the top chord 25 so that these caps will always be guided to a certain extent in their vertical movement. These caps 8 are also provided with projecting lugs 35 reinforced by webs 36 as shown in Figs. 11 12 and 13 and at their upper ends they are provided with seats 37 for the pins 38 of the stirrup 39 which carry the ends of the upwardly arched semi-elliptic springs 9. This mounting of the semi-elliptic springs permits them to spread slightly at their supports, as is obvious. Each semi-elliptic spring 9 is provided with a band 40 which has two ears 41 through which extend bolts 42 and each bolt 42 carries two links 43, one link at each end of each ear 41. Springs 44 are placed on each bolt 42 adjacent to the nut 45 so that any desired pressure may be placed on the links 43 which will prevent a too free movement of said links. The lower ends of said links 43 are united by a plate 46 which has ears 47 corresponding to the ears 41 and bolts 48 connect these ears and links 43, as shown, so that the plate 46 is always parallel to the band 40 and has a parallel movement therewith, transversely of the truck. The bolster 10 is secured to said plate 46 by means of bolts 49 which extend through the same. This bolster 10 consists of a lower bar 50 with upturned ends 51 against which abuts the upper bar 52. Above each plate 46 the bars 50 and 52 are parallel and between the plates 46 these bars are separated by the filler 53 and all parts are held together by means of bolts 54. The upper bar

52 is also provided with a side bearing 55 which may be of any suitable form and a center bearing 56. The side bearings 55 are preferably made so as to rub against the rub plates 28.

From the foregoing, the action of my improved truck will be readily understood. The car body rests on the bolsters of the trucks, each bolster carrying one-half the weight in the following manner: The bolster 75 transmits this weight to the plates 46 which transmit the stresses through the four links 43 to the band and from thence to the upwardly arched leaf-springs 9 which are somewhat straightened in consequence and spread 80 the stirrup 39 to some extent. The stresses not taken up by the springs 9 are transferred to the equalizing springs 7 through the caps 8. From thence the weight is transmitted through the spring seats to the equalizing 85 bars 6 and from thence to the axle boxes 4, axles 3 and wheels 2. The axle boxes 4 have connections without springs with the equalizing bars 6 through the cylindrical bearings and they are connected to the frame 5 and to each other by the bars 14 which are pivotally connected with said axle boxes. This permits a certain flexibility of movement of the axle boxes to correspond to the inequalities of the track and it also provides 90 that the motors and brake gear may be supported from the equalizing bars so as to be independent of the spring system of the truck. The truck frame is also independent 95 of the spring system of the truck and the 100 bolster transmits the stresses incident to its use, through the spring system of the car to equalizing bars without disturbing in any way any other portion of the truck.

While I have shown and described one embodiment of my invention, it is obvious that it is not restricted thereto, but is broad enough to cover all structures that come within the scope of the annexed claims.

Having described my invention what I 110 claim is:

1. In a truck of the class described, axle boxes and means for supporting the same, tie bars connecting said axle boxes and a top frame secured to said tie-bars resting on said axle boxes, equalizing bars supported by said axle boxes, equalizing springs supported by said equalizing bars, a bolster and means for carrying said bolster from said equalizing springs and independent of said truck frame. 115 120

2. In a truck of the class described, axle boxes and means for supporting the same, tie bars connecting said axle boxes, equalizing bars supported by said axle boxes, a truck frame secured to said tie bars, a bolster, and means for supporting the same from said equalizing bars and independent of the truck frame. 125

3. In a truck of the class described, equalizing bars and means for supporting the 130

same, equalizing springs carried by said bars, caps on said springs, leaf springs carried by said caps, a bolster and means for carrying said bolster from said leaf springs.

5 4. In a truck of the class described, a frame composed of top chords extending downwardly on one side of each pedestal, tie bars uniting said top chords and transoms resting on said top chords and secured thereto.

10 5. In a truck of the class described, equalizing springs and means for supporting the same, caps on said springs and a truck frame above parts of said caps and between other parts, upwardly arched leaf springs having their ends mounted on stirrups supported by said caps, bands on said springs, links pivotally connected with said bands and plates connecting the lower ends of said links and a bolster carried by said plates.

15 6. In a truck of the class described, semi-elliptic springs and means for supporting the same, bands on said springs, links pivotally connected with said bands and bolster and means for supporting said bolster from said links, and springs for regulating the pressure of said links against said bands.

20 7. In a truck of the class described, equal-

izing bars with saddles, axle boxes with cylindrical surfaces on which said saddles rest, downwardly extending lugs on said axle 30 boxes and tie bars connecting the lugs of axle boxes on the same side of the truck whereby said axle boxes will always be kept in proper relation.

8. In a truck of the class described, equalizing bars, saddles having cylindrical seats supporting said bars, axle boxes having cylindrical surfaces on which said seats rest, downwardly extending lugs, tie-bars connecting said lugs on said axle boxes, and a 35 truck frame supported by said tie-bars.

9. A truck of the class described, axle boxes having depending lugs, tie bars, brackets connecting said tie bars and lugs and bolts with springs thereon adapted to hold 40 said brackets and lugs in their proper relations.

Signed at the city and county of Philadelphia, State of Pennsylvania, this 14th day of September, 1908.

WALTER S. ADAMS.
